UNITED STATES PATENT OFFICE.

OSCAR ZERK, OF CLEVELAND, OHIO, ASSIGNOR TO THE ZERK MANUFACTURING COMPANY, OF CLEVELAND, OHIO, A CORPORATION OF OHIO.

GREASE-CUP.

1,031,409.

Specification of Letters Patent. Patented July 2, 1912.

Application filed August 16, 1911. Serial No. 644,423.

To all whom it may concern:

Be it known that I, OSCAR ZERK, a subject of the Emperor of Austria-Hungary, residing at Cleveland, in the county of 5 Cuyahoga and State of Ohio, have invented a certain new and useful Improvement in Grease-Cups, of which the following is a full, clear, and exact description, reference being had to the accompanying drawings.

10 The object of this invention is to provide a simple and efficient grease cup arranged with a revoluble cap and a movable plunger within the cap depressed by rotating the cap. This enables the structure to be 15 extremely neat in appearance, as well as very efficient in preventing leakage, while the grease may be effectively forced downward as fast as desired.

The invention comprises the means I have 20 employed to this end, as hereinafter more fully explained and as definitely set out in the claims.

The drawings clearly disclose my invention.

25 Figure 1 is a side elevation of the complete grease cup; Fig. 2 is a vertical section thereof; Fig. 3 is a cross section of the grease cup, looking upward.

In the drawings, the body of the grease 30 cup is designated 10. It is a cup-like structure having a cylindrical wall and a bottom 11 and an externally threaded nipple 12 projecting from the center of the bottom. This nipple has a bore 13 extending through 35 the bottom and flaring upwardly. Near the lower edge of the cylindrical wall it is preferably formed with angular or hexagonal faces 15 whereby, by a suitable wrench, the grease cup may be screwed into place.

40 The interior surface of the cup wall is provided with a continuous screw thread 16. Engaging this thread is a suitable plunger 20 which is shown as a sheet metal member having an edge flange 21 which is screw- 45 threaded to engage the threads 16. Obviously, if the plunger 20 is rotated in the proper direction, it will descend in the body or cup and compress the grease therein.

50 30 designates a suitable cap which extends over the top of the body and has a downward cylindrical flange 31. This flange is provided on its interior with a rabbeted edge 32 so that the flange both rests on the top of the cylindrical wall 10 and also ex-

tends downwardly outside of that wall. The 55 flange of the cap is preferably knurled, as shown in Fig. 1, so that it may be conveniently grasped for rotation. The head of the cap may be bowed upwardly, as shown. In that case the head of the plunger 20 is 60 also bowed upwardly. This arrangement adds to the neatness of appearance as well as increasing the capacity of the cap.

Extending through the cap and plunger and locking them together as far as rotation is concerned is a bar 40. This bar is flat and occupies correspondingly shaped openings in the plunger and cap. Above the cap the bar is preferably provided with a T-head 41. This T-head furnishes an 70 additional means for rotating the plunger. When the bar, plunger and cap are turned, by rotating the cap or the bar, the plunger, by reason of the screw-threads, travels up or down in the body of the cup, according to 75 the direction of rotation.

50, in Fig. 2, designates a suitable packing disk within the flange of the plunger 20 and snugly surrounding the bar 40 and preventing leakage of grease. This disk 80 may be of cork, or any suitable material. Below the packing washer and surrounding the bar 40 is a helical compression spring 60, preferably of the flaring type shown. The largest coil of this spring rests against 85 the washer within the flange 21 of the plunger. The smallest coil bears against a small washer 70 surrounding the bar 40 near its lower end, this small washer resting against a suitable cotter pin 80 projecting through 90 the bar below the washer.

In the construction described the spring 60 causes proper friction of the cap 30 against the top of the wall 10 at the rabbet 32, as well as friction of the plunger with 95 the thread 16. This prevents any inopportune turning of the cap. At the same time, whenever desired, the cap may be conveniently turned by the fingers, either grasping the knurled surface or the head 41, to feed 100 the grease or to remove the cap and plunger for reloading. When the cap and plunger are removed, the removal of the cotter pin allows the separation of the various parts for repair, should it be desired. When the 105 cap is put in place the threads on the flange 21 engage with the threads 16 before the cap abuts the wall and until such abutting

takes place the cap turns very freely. Then, when the cap begins to turn hard, the operator at once knows that the parts are in position for use. It will be observed that the spring not only causes the proper friction to prevent inadvertent turning, but keeps the washer 50 compressed and in place within the plunger to prevent leakage.

Having thus described my invention, what I claim is:—

- 10 1. In a device of the character described, the combination of a cup-like body internally threaded, a plunger externally threaded, a cap rotatable on the body, a bar rotatable with the cap and extending slidably through the plunger, and a spring opposing the travel of the plunger along the bar.
- 20 2. In a device of the character described, the combination of a cup-like body internally threaded, a plunger externally threaded, a cap extending over the plunger and adapted to bear against the wall of the body, a bar rotatable with the cap and extending slidably through an opening in the plunger, and a compression spring surrounding the bar and held near the lower end of the plunger and tending to oppose the movement of the plunger into the body.
- 30 3. In a device of the character described, the combination of a cup-like body internally threaded, a plunger formed with an externally threaded downward flange cooperating with the internal threads of the body, a cap, a bar rotatable with the cap and rotatable with the plunger, the plunger being slidable on the bar, and a flaring coiled compression spring surrounding the bar, the large coil of the spring being within the flange of the plunger, and the small coil bearing against a stop at the lower end of the bar.
- 40 4. In a device of the character described, the combination of a cup-like body internally threaded, an externally threaded plunger within the body, a flanged cap extending over the plunger and over the outer wall of the body, the flange being formed with a rabbet to rest on the top of the body wall, means for preventing independent rotation of the cap and plunger while allowing them

to relatively separate, and a spring opposing such separation.

5. In a device of the character described, the combination of a cup-like body internally threaded, a plunger having a downward flange externally threaded to coöperate with the internal threads of the body, a cap extending over the plunger and bearing against the body, an angular bar extending through the cap and plunger, the plunger being slidable on the bar, packing material around the bar within the flange of the plunger, and a spring surrounding the bar and compressed between the packing material and the lower end of the bar.

6. In a device of the character described, the combination of a cup-like body having internal threads, a coöperating plunger having external threads, a cap extending over the plunger and having a flange bearing against the body, a bar formed with a head and extending through an angular central opening in the cap and plunger, and a spring surrounding the bar and compressed between the lower end of the bar and the under side of the plunger.

7. In a device of the character described, the combination of a cup-like body having an exit opening at its bottom and threads on the interior of its wall, a downwardly flanged plunger externally threaded to coöperate with such wall, a downwardly flanged cap adapted to extend over the plunger and having its flange rabbeted to rest on the upper edge of the body wall, a flat T-shaped bar, the shank of which extends loosely through aligned openings in the cap and plunger, a packing washer surrounding the bar within the flange of the plunger, a flaring coiled compression spring surrounding the bar and having its large coil within the flange of the plunger and its small coil suitably held adjacent to the lower end of the bar.

In testimony whereof, I hereunto affix my signature in the presence of two witnesses.

OSCAR ZERK.
